Specification for Design.

Patented Apr. 3, 1917.

Application filed December 8, 1916. Serial No. 135,913. Term of patent $3\frac{1}{2}$ years.

To all whom it may concern:

Be it known that I, JOHN H. HILDEBRANDT, a citizen of the United States, residing at Salina, in the county of Saline and State of Kansas, have invented a new, original, and ornamental Design for Hammer-Heads, of which the following is a specification, reference being had to the accompanying drawing, forming a part thereof.

In the drawings:—

Figure 1 is a side elevation of the hammer head;

Fig. 2 is a top plan view of the hammer head;

Copies of this patent may be obtained for five cents each, by addressing the "Commissioner of Patents, Washington, D. C."

Fig. 3 is a bottom plan view of the hammer head;

Fig. 4 is a sectional view taken on line 4—4 of Fig. 1.

I claim:

The ornamental design for a hammer head, as shown.

In testimony whereof, I affix my signature in presence of two witnesses.

JOHN H. HILDEBRANDT.
